UNITED STATES PATENT OFFICE.

HENRY GODDARD TUCK, OF SYDNEY, NEW SOUTH WALES, AUSTRALIA.

PROTECTIVE STOPPER FOR BOTTLES.

1,331,730.

Specification of Letters Patent. Patented Feb. 24, 1920.

Application filed December 28, 1918. Serial No. 268,708.

To all whom it may concern:

Be it known that I, HENRY GODDARD TUCK, a subject of the King of Great Britain and Ireland, residing at Sydney, in the 5 State of New South Wales, Commonwealth of Australia, have invented certain new and useful Improvements in Protective Stoppers for Bottles, of which the following is a specification.

10 This invention relates to improvements in the stoppering of bottles and refers essentially to a means of preventing or rendering difficult the fraudulent refilling of bottles such as in the ordinary way contain the 15 higher grades or kinds of spirituous liquors such as whisky or other beverages or liquids.

The invention comprises an annular cuffed groove in the mouth of the bottle; a valve of glass or its equivalent adapted 20 to seat in said groove and having on its under face a weighting and centering stem and on its upper face a concentric recess into which is adapted to take a guide tongue depending from a domed and perforated cap 25 that rests on an elastic washer surrounding the mouth of the bottle; a centrally perforated disk overlying the valve and resting on the bottle mouth and adapted to move on the said guide tongue; a disk 30 adapted to externally cover the perforations in the domed cap, and a strong covering capsule. But in order that the invention may be clearly understood reference will 35 now be made to the drawings which accompany and form part of this complete specification and in which:

Figure 1 is a vertical section of a bottle neck showing the improved stopping appliance fitted in the mouth thereof.

40 Fig. 2 is side elevation of domed cap.

Fig. 3 is top plan of same.

Fig. 4 is centrally perforated disk.

Fig. 5 is elastic washer to be placed on flange surrounding bottle mouth.

45 Figs. 6, 7 and 8 are respectively a top plan, an underneath plan, and a side elevation of valve.

Fig. 9 is external covering disk of domed cap.

50 The bottle neck 1 has at its mouth an annular cuffed seating 10 of sufficient depth to retain a small quantity of liquid. The valve 11 rests in the seating 10 and is weighted and centered in the neck of the bottle by stem 12 which may be radial as shown, or of any other well known construc-

tion which will allow the liquid to pass. On the top face of the valve 11 a concentric recess or cavity 13 is formed. Overlying the valve 11 and resting on the top edge of the 60 bottle mouth is a disk 14 having a concentric aperture 15 of the same diameter as recess 13 in valve. Surrounding the bottle mouth is a flange 16 on which is laid a washer 17 preferably of cork, and on this washer rests 65 the lower edge of a domed cap 18 that has perforations 19 and a downwardly projecting tongue 20 which passes through aperture 15 in disk 14 and centers recess 13 in valve 11. A disk 21 is placed on the top 70 of cap 18 so as to cover the perforations 19. The center portion which is removed from cork disk to form the washer 17 can be suitably and economically utilized for the covering disk 21. A strong metal capsule 22 75 of sheet aluminum or the like is placed over the cap and spun or otherwise drawn into close contact with the cap and bottle neck thus securing the appliances in position and sealing the bottle.

In operation—when it is desired to unseal the bottle the covering disk 21 is removed by cutting the capsule between the disk 21 and the top of the cap 18. The perforations 19 in cap 18 are then exposed 80 while at the same time the cap 18 is still held firmly in position by reason of the close fitting capsule surrounding it. When the bottle is tilted the pressure of liquid therein causes the valve 11 to leave its seat 90 10 and move along the guide tongue 20 carrying with it the disk 14 (as shown in dotted lines Fig. 1) thus leaving an annular space through which the liquid passes to the perforations 19 in top of cap 18 through the 95 lower half of which it escapes from the bottle while air enters the bottle through the upper perforations thus insuring a strong and uniform flow. When the bottle is brought into the vertical position again 100 the valve and disk drop into position, the former being sealed and the latter preventing any interference with the valve through the perforations 19, a boss or the like 23 is provided at the root of the guide tongue 105 20 to prevent the washer 14 coming into contact with the top of the cap when the bottle is tilted and blocking the perforations.

I claim:

An improved protective stopper for bottles comprising in combination a valve adopted to be liquid sealed in a cuffed

seating within the bottle mouth and having on top a concentric cavity and underneath a weighting and centering stem; a domed and perforated cap resting with intermediate washer on a flange surrounding the mouth of bottle and having a depending guide; a disk overlying the said valve; an external sealing disk overlying the perforation in said cap, and a strong covering

capsule substantially as and for the purpose herein set out.

In testimony whereof I have affixed my signature in presence of two witnesses.

HENRY GODDARD TUCK.
